UNITED STATES PATENT OFFICE.

JOHN H. WAIT, OF PORTSMOUTH, OHIO.

ATTACHMENT FOR GRATES.

SPECIFICATION forming part of Letters Patent No. 399,098, dated March 5, 1889.

Application filed September 8, 1888. Serial No. 284,905. (No model.)

To all whom it may concern:

Be it known that I, JOHN H. WAIT, a citizen of the United States, residing at Portsmouth, in the county of Scioto and State of Ohio, 5 have invented new and useful Improvements in Attachments for Grates, of which the following is a specification.

My invention relates to improvements in attachments for grates; and it consists in certain novel features, hereinafter described and claimed.

Figure 1 of the drawings is a perspective view of a portion of a grate having my improved attachment applied thereto. Fig. 2 is 15 a detail perspective view of my improved device detached from the grate. Fig. 3 is a side view showing a modified form of the device. Fig. 4 is a similar view showing another modification.

Referring to the drawings by letter, A designates a grate of ordinary construction having the usual grate-bars, B.

C designates my improved device, consisting of a casting comprising a plate, D, composed of a number of bars having grooves E in their upper surfaces, and provided with a handle, F, projecting from its front end. This construction of the plate provides a number of openings, G, so that by reason of said 25 grooves and openings its weight and cost will be reduced to a minimum. The central opening G, at the front end of the plate, is smaller than the others, so as to be engaged by an ordinary stove-lifter to be removed from the 30 grate. On its under side the plate is provided with the integral depending feet or prongs H, which are adapted to pass down on opposite sides of the grate-bars, and thereby support the attachment in position, as shown in Fig. 1.

These prongs or feet are of unequal length 35 and are arranged near the rear end of the plate, the front foot being the longer. The greater portion of the plate is thus supported in front of the grate out of direct contact with the fire, and is prevented from tipping by the feet bearing against opposite sides of the grate-bars. By making the rear legs small enough to pass between two adjacent grate-bars the device may be adjusted to any desired height.

My improved attachment is designed for supporting cooking utensils in front of and

over the fire, so that they may be readily handled without inconvenience or danger to the operator, and at the same time the food be speedily and thoroughly cooked. When arranged as shown in Fig. 1, the cooking utensils will be held in front of the fire. The devices can be arranged, however, to support the cooking vessels over the fire by allowing the front edge of the plate to rest on the upper grate-bar and the feet or prongs rest on the bottom of the grate at the rear edge thereof. When the device is arranged over the fire, the openings permit the heat to pass directly to the vessel.

In Fig. 3 I have shown my device as provided with only one foot on each side, the said foot depending from the rear end of the plate. From the rear side of the said feet, near the upper ends of the same, project the rearwardly 70 and upwardly curved hooks I, having square shoulders J on their lower edges adjacent to the feet. This form of my device is designed more especially for attachment to the lower grate-bars, but can be applied to any of them. 75 It is secured in position by being turned into a vertical plane, so as to enable the hooks I to pass between the adjacent grate-bars, and it is then swung outward and downward, causing the said hooks to pass upward in rear of 80 the upper one of the grate-bars, and enabling the shoulders J to clear the lower grate-bar and slip into engagement with the rear side of the same, the feet bearing against the front side of the grate-bars, so that the device will 85 be firmly locked in its place. The shoulders J in this form bear against the rear sides of the grate-bar, and serve the same purpose as the smaller prongs in the form previously described.

In Fig. 4 I have shown a further form of my device, which is designed especially for attachment to the first and second grate-bars. In this form the plate is provided on its under side with a depending lug, K, having the 95 rear curved edges, L, and provided with the small angular notch M in rear of said rear curved edge. From the under side of the plate, near the rear edge of the same, depend the feet N, which are given a slight rearward 100 inclination, as shown, and are provided at their lower ends with the prongs O, the lower

edge of the feet between the prongs being curved, as shown, and provided with a notch, P. The front edges of the feet are curved upward, rearward, and then upward again to 5 the notches M, so as to clear the grate-bars when the device is being placed in position. This form of the device is placed in position by being first turned to a vertical position in rear of the upper grate-bar and causing the 10 prongs O to engage the second grate-bar, after which the device is turned forward and downward, so as to bring the lugs K into engagement with the upper grate-bar, the notches M and P engaging the upper rear edges of the 15 respective grate-bars, so that the device will be firmly held in place. To disengage the device from the grate, it is first slightly lifted and then turned in a reverse direction.

It will be observed that in all the forms of 20 my device the supporting-legs are below the plate, so that the device and the vessel supported thereby can be placed nearer the heat than if the plate were supported from a point above the grate.

Having thus described my invention, what 25 I claim, and desire to secure by Letters Patent, is—

1. An attachment for grates, comprising a flat plate having a series of grooves in its upper surface and a number of openings, G, the 30 front central opening being of proper size to be engaged by a lifter, and feet or prongs depending from the under side of the plate at the rear end of the same, as specified.

2. An attachment for grates, consisting of a 35 flat plate having on its under side at its rear end the lugs K and notches M, and the depending feet N, provided with the prongs O O at their lower ends, substantially as and for the purpose specified. 40

In testimony that I claim the foregoing as my own I have hereto affixed my signature in presence of two witnesses.

JOHN H. WAIT.
